ELMER L. SMITH, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

STRIP FEEDING AND CUTTING MECHANISM.

1,313,862.

Specification of Letters Patent.

Patented Aug. 19, 1919.

Application filed February 5, 1919. Serial No. 275,186.

To all whom it may concern:

Be it known that I, ELMER L. SMITH, a citizen of the United States of America, residing at Springfield, in the county of 5 Hampden and State of Massachusetts, have invented certain new and useful Improvements in Strip Feeding and Cutting Mechanism, of which the following is a specification.

10 This invention relates to improvements in strip feeding and cutting mechanism.

Many examples of strip feeding and cutting mechanism will be found in the prior art and the present invention is concerned 15 more particularly with an improvement associated with strip feeding and cutting mechanism of particular types to eliminate difficulties heretofore encountered with such types of mechanisms. Briefly, the feeding 20 mechanism is of the type in which the strip is fed by a pushing, rather than a pulling, action to a position beyond the cutting mechanism, and the latter is of the type in which a movable severing blade coöperates with a fixed severing blade.

Practical experience with this type of feeding and cutting mechanism has shown 30 that there is, under certain conditions, a tendency for the end of the strip to stick to the fixed severing blade after it has been severed, so that, when the feeding mechanism comes into play after the cutting operation, the strip, by reason of its adherence 35 to the blade, will not be readily pushed past the blades, but will pile up in the paper feed chute and clog the latter. The difficulty mentioned is accentuated when the fed strip is foil or waxed paper or the like. The trouble can be reduced to a considerable 40 extent if the severing blades are provided with a very keen edge, but to cure the difficulty in this manner necessitates frequent removal and sharpening of the blades to maintain their edges at the high degree 45 of keenness necessary.

This invention has for its object to provide, in combination with a strip feeding and a strip cutting mechanism of the type disclosed, a device to strip the end of the 50 fed strip from the cutting blade shortly after the cutting operation and before the feeding mechanism, which is intermittently operable, again comes into play.

Other objects of the invention will appear

in the following description and in the illustrative embodiment of the invention, in the accompanying drawings, in which:

Figure 1 is an elevational view of a strip feeding and cutting mechanism embodying the invention;

Fig. 2 is a sectional plan view thereof showing the cutting mechanism and the stripping device;

Fig. 3 is an enlarged fragmentary cross-sectional view taken on the line 3—3 of Fig. 2; and

Fig. 4 is a fragmentary perspective view of one of the cutting members.

Referring to these drawings, the strip feeding mechanism includes, essentially, 70 simply some means to push the strip to and beyond the cutting mechanism. As an illustrative example of one suitable type of feeding mechanism, two coacting rolls 5 and 6 are shown, which rolls revolve in opposite 75 directions and, by gripping the strip therebetween, feed it, by pushing, into a guide chute 7. In this instance, the feeding of the strip is aided slightly by gravity, since the strip *a* passes vertically downwardly 80 into the chute 7, but the aid of gravity acting on the light strip *a* is, of course, not sufficient to overcome the prior difficulties mentioned.

The strip cutting mechanism is mounted 85 adjacent the lower end of chute 7 and is suitably arranged to operate on strip *a* only after a predetermined length thereof has been fed past the cutting mechanism and into a second chute 8, which is aligned with 90 but spaced below the described chute 7. This strip cutting mechanism includes, essentially, a movable cutting member, as the knife blade 9, which coöperates with a suitable fixed surface, as that afforded by 95 the complementary stationary knife blade 10 shown, to sever the strip *a*, which is fed between the blades.

The means for stripping the strip *a* from the blade 10, to which it sometimes tends to adhere, comprises a blade 11 which is substantially coextensive in width with the strip *a* and is pivotally supported, to swing in close proximity to the cutting edge of the stationary blade 10. The stripper 11 is supported by a pair of arms 12 from a shaft 13, the arms being fixed to the latter. The shaft 13 is arranged to be rocked, as the

blade 9 is moved away from blade 10, to carry the stripper 11 against the strip *a* and insure that the latter does not adhere to blade 10. This function is accomplished by means of a projection 14 carried by the movable blade 9 and arranged to engage an arm 15 secured to shaft 13.

Referring more particularly to the details of the machine shown to illustrate the invention; the strip feeding mechanism, the rolls 5 and 6, are mounted on shafts 16 and 17, respectively, which shafts are journaled in two spaced side frames A (one only being shown in the drawings). Frames A are supported by columns B from a suitable main frame or bed plate C. The strip *a* is provided in roll form, the roll being supported on an arbor 18 which is also journaled in frames A. The strip *a* is led from this roll over suitable guiding means, as the roll 19 (also supported by frames A) to and between the feed rolls 5 and 6 and thence downwardly into chute 7.

The feed rolls 5 and 6 may conveniently be driven in the following manner. Their shafts 16 and 17 are connected at one end by intermeshing gears 20, indicated in dotted lines in Fig. 1. Fixed on the other end of shaft 16 is a pinion 21, which is driven by a gear 22 loosely mounted on the other end of shaft 17. Fixed to gear 22 is a ratchet 23 and, adjacent the ratchet and loosely mounted on shaft 17, is an arm 24, which carries a pawl 25 to engage the ratchet. Arm 24 is connected by a link 26 with one end of a lever 27, which is pivoted intermediate its ends to frame C and carries on its other end a roll to ride in a suitable path cam 28. The latter is fixed to a shaft 29, which is suitably supported from bed C and is adapted to be driven by any suitable means.

The chute 7 is supported by and between two cross-bars 30, one of which is secured at its ends to brackets D (one on each of the described columns B). To one of the brackets D (the rear as viewed in Fig. 1) the movable blade 9 is pivoted by a stud 31. The stationary blade 10 is also supported on stud 31 and is stationarily held to one of the cross-bars 30 by a bracket 31'. Blade 9 has a rearward extension 32, which is connected by a link 33 with the upper end of a lever 34, pivoted intermediate its ends to bed C. The lower end of lever 34 bears a roll which is arranged to ride in a suitable path cam 35 fixed on shaft 29.

The stripper blade 11, as described, is fixed on a rock shaft 13 and this shaft is supported near its ends by brackets 36 secured to one of the cross-bars 30 described. The arms 12, which, as described, support blade 11 from shaft 13, have upwardly extending parts 37, which are adapted to engage the left-hand cross-bar 30 and limit the

swinging movement of blade 11 in a clockwise direction (Fig. 3). Fixed to and depending from the right-hand cross-bar 30 are a pair of arms 38 the lower ends of which are arranged in the path of arms 12 and are adapted to engage the latter to limit the counterclockwise swinging movement of the blade 11. A torsion spring 39 (Fig. 2) is coiled about one end of shaft 13 and has one end affixed to the latter (or as shown to an adjustable collar 40 thereon.) The other end of spring 39 is fixed to the adjacent bracket 36. The spring 39 is so arranged that it tends to swing shaft 13 in a counterclockwise direction (as viewed in Fig. 3) and thus yieldingly holds blade 11 in the illustrated position, wherein arms 12 abut the stop arm 38.

The projection 14, which as described is arranged to abut the lower end of arm 15 and rock blade 11 in a clockwise direction, is part of a block 41, which is preferably secured to blade 9 by a strip 42 of spring metal (Fig. 4). Thus, after the projection 14 has engaged and moved arm 15 until stop arms 37 have abutted the cross bar 30, the block 41 may be cammed downwardly on further movement of blade 9 to permit the passage of the block past the arm 15. This construction is desirable where the block is carried (as shown in Fig. 4) on the free end of the movable knife blade, for the latter at its free end has a considerable range of movement while the range of movement of the rock blade 11 is relatively small. As the movable blade 9 moves toward blade 10, the block 41 is again cammed downwardly by arm 15, an easy incline 43 being provided on block 41 for this purpose.

In operation, the cams 28 and 35 are so constructed and arranged that the feed rolls 5 and 6 are rotated while the blades 9 and 10 are held in separated relation. The rolls 5 and 6 are turned through a predetermined degree of angular movement and thus feed a predetermined length of strip *a* past the shear blades 9 and 10. The rotation of the feed rolls 5 and 6 is accomplished on an up-throw of lever 27 and, on the downthrow, the pawl 25 rides idly over the teeth of ratchet 23 without turning the latter or the feed rolls. During the period of time occupied by the downthrow of lever 27 and during a further period if necessary, in which the lever 27 dwells in its lower position, the cam 35 causes the blade 9 to be moved toward blade 10 to sever the strip *a*. The cam 35 then moves blade 9 away from blade 10 and holds it in open position until a succeeding cycle of operation of the feeding mechanism. The latter, for the purpose of speeding up the machine as far as possible, is timed to commence its feeding movement immediately as the strip *a* is released by blade 9. The stripper 11, being operated by

the projection 14 on the outer end of blade 9, thus comes into play near the very start of the opening movement of the blades so that it is insured that strip *a* will be removed from blade 10 before the start of the feeding movement. It is, thus, important to have the stripper 11 operated by the free end of the movable shear blade. However, by so doing, the range of movement of the 5 movable shear blade is more than is desired for operation of the stripper 11, so the stop arms 37 and the yieldable support for projection 14 are important,—the former since it positively arrests the stripper at a time 10 such that the lower end of strip *a* is freed from blade 10 and positioned substantially centrally above the guide chute 8, into which it must pass; and the latter since it permits the stripper 11 to be operated a relatively short distance by a member which 15 moves through a much longer distance.

It is generally found in practice that the severed end of the strip *a* tends to adhere to the stationary blade 10. Sometimes, 20 however, when the movable blade 9 is duller than the fixed blade 10, the severed end of the strip will adhere to the former. The adherence of the strip to the movable blade will not cause difficulty for the severed end 25 will be stripped by other means, on the opening of the shears. Thus, as shown in Fig. 3, the left-hand wall of chute 7 is carried into close proximity with the upper surface 30 of blade 9, so that the lower end of such 35 wall will strip the severed end of strip *a* from the blade 9 as the latter is moved away from blade 10.

The invention has been disclosed herein in a preferred embodiment for illustrative 40 purposes, but the scope of the invention is defined by the appended claims rather than by the foregoing description.

What I claim is:—

1. In combination, a strip cutting mechanism having a stationary and a movable shear blade, mechanism to feed a strip by pushing the latter to and beyond the blades while the latter are held in separated relation, means to actuate the movable blade so 45 that the latter is advanced to sever the strip and then returned, and means movable by and operable on the return of said blade to engage the strip and force it away from said stationary blade.

2. The combination with strip feeding mechanism, of shears arranged in advance of the feeding mechanism to sever the strip fed by the latter, said shears having only one movable blade, and means controlled by 50 the opening of the shears to positively move the severed end of the strip away from the stationary blade.

3. The combination with web cutting mechanism, which includes a fixed and a 55 movable shear blade and means to open and

close them at properly timed intervals, of mechanism behind the cutting mechanism to feed the web to the latter, a stripping device mounted for movement in close proximity to the fixed shear blade and arranged 70 to engage the severed end of the web and strip it from the latter, and a part yieldably secured near the free end of the movable blade to actuate said device.

4. The combination with web cutting mechanism, which includes a fixed and a movable shear blade and means to open and close them at properly timed intervals, of mechanism behind the cutting mechanism to feed the web to the latter, a stripping device mounted for movement in close proximity to the fixed shear blade and arranged 75 to engage the severed end of the web and strip it from the latter, stops to limit the movement of said device in each direction, 80 means yieldingly holding the device against one of said stops, and a part yieldably secured near the free end of the movable blade and engageable on the opening of the shears with said device to move it against the other 85 stop.

5. The combination with web cutting mechanism, which includes a fixed and a movable shear blade and means to open and close them at properly timed intervals, of 90 mechanism behind the cutting mechanism to feed the web to the latter, a pivoted stripping blade mounted to swing in close proximity to the cutting edge of the fixed shear blade, means to limit the swinging movement of the stripping blade in one direction, 95 means yieldingly holding the stripping blade against the first-named means, a stop to limit the movement of the stripping blade in the other direction, an arm movable with 10. the stripping blade, and a projection yieldably secured to and near the free end of the movable shear blade and engageable on an opening of the shears with said arm, whereby the stripping blade is actuated to strip 105 the web from the fixed shear blade, said projection arranged to be deflected by and away from said arm on continued movement of the movable shear blade after the stripping blade has been arrested by said stop.

6. The combination with web cutting mechanism, which includes a fixed and a movable shear blade and means to open and close them at properly timed intervals, of mechanism behind the cutting mechanism to feed the web to the latter, a pivoted stripping blade mounted to swing in close proximity to the cutting edge of the fixed shear blade, means to limit the swinging movement of the stripping blade in one direction, 110 means yieldingly holding the stripping blade against the first-named means, a stop to limit the movement of the stripping blade in the other direction, an arm movable with the stripping blade, a projection yieldably 115 secured to and near the free end of the movable shear blade and engageable on an opening of the shears with said arm, whereby the stripping blade is actuated to strip the web from the fixed shear blade, said projection arranged to be deflected by and away from said arm on continued movement of the movable shear blade after the stripping blade has been arrested by said stop.

120

125

130

cured to and near the free end of the movable shear blade and engageable on an opening of the shears with said arm, whereby the stripping blade is actuated to strip the web 5 from the fixed shear blade, said projection arranged to be deflected by and away from said arm on continued movement of the

movable shear blade after the stripping blade has been arrested by said stop, and a cam associated with said projection to permit the latter to be readily deflected by said arm on the closing of said shears. 10

ELMER L. SMITH.
